UNITED STATES PATENT OFFICE

MILo A. BAKER, OF LOS ANGELES, CALIFORNIA.

BELT-GEARING.

No. 920,519.

Specification of Letters Patent.

Patented May 4, 1909.

Application filed October 5, 1908. Serial No. 456,343.

To all whom it may concern:

Be it known that I, MILo A. BAKER, a citizen of the United States, residing at Los Angeles, in the county of Los Angeles and State 5 of California, have invented a new and useful Belt-Gearing, of which the following is a specification.

The object of the present invention is to provide means for transmitting motion between two rotary members, for example, the extra bull wheel or calf wheel and the outer tug wheel on the band wheel shaft of a well drilling rig. For such purposes a single endless rope or cable is generally used, passing 10 over grooved pulleys on the aforesaid wheels, and under the conditions of practice said rope has been of such size that it becomes unduly stiff for easy running. In order to provide the proper strength and tractive power of the 15 rope and at the same time provide for flexibility, the rope or cable, according to my invention, is doubled, so that, although it is endless, it presents a double strand throughout. This necessitates crossing of the two 20 strands at a part of the closed circuit, and the tension of the rope is so maintained that the point of crossing is always maintained on one run of the combined rope, so that effective contact of both strands with the pulleys 25 is always maintained.

The accompanying drawings illustrate the invention:

Figure 1 is a plan of the two wheels with the cable means connecting the same. Fig. 35 2 is a vertical section of one of said wheels with the cable thereon. Fig. 3 is a side elevation of two wheels and the cable, and Fig. 4 is a diagrammatical perspective showing the complete course of the cable. Fig. 5 is a 40 side elevation of a portion of the driving wheel.

1 designates a driving wheel which may, for example, as stated, be the outer tug wheel on the band wheel shaft 2, of a drilling 45 wheel, and 3 represents the driven member which may be the calf wheel of the rig, provided with a grooved rim 4 to receive the driving cable 5. Said cable forms an endless or closed circuit and is doubled so that 50 it provides a double strand throughout its length, two strands lying side by side. The grooves 6, 7 of the two wheels 1, 3 are of sufficient width to receive these two strands side by side and allow each strand to come into 55 effective contact with the bottom of the groove for traction thereon. As the cable

forms a continuous or endless circuit it follows that at some point in its course there is a crossing of one strand over the other and the tension of the rope is such that the pressure of the rope on the wheels forces the two strands to lie flat, and side by side, against each wheel so that the crossing is prevented from passing onto either wheel but remains on the same run in which it was originally 60 formed, the tension on the two strands in advance of the point of crossing causing the crossing to continually recede along the cable as the cable advances over the wheel. The two strands of cable run side by side and 65 in contact not only where they pass around the wheels but throughout the upper and lower runs. The effect of this is to minimize the lateral movement of the cable and therefore reduce to a minimum the wear and friction where the strands cross one another, as 70 the crossing is effected simply by one cable rolling over the other instead of by lateral sliding. It is found that by this construction the loss in friction and the wear and 75 tear on the rope due to bending is considerably less than a cable of double cross section such as would be necessary to transmit the same power and the doubled rope being 80 more flexible is also easier to put in place and 85 to handle. This greater flexibility also enables it to work more freely on the wheels and to take a better grip thereon. One side 90 flange 6', for example, of the wheel 1, has a notch or cut away portion 8 to facilitate insertion and removal of the cable onto or from the wheels. The walls 8' of said slot extend laterally beyond the face of the wheel 1. This notch shipping and unshipping means 95 is of especial advantage in well drilling rigs, 100 in the connection stated, as it is necessary in such rigs to frequently change the belts so as to drive one part or another of the mechanism.

What I claim is:

1. The combination with two wheels, of a cable connecting the same, said cable constituting an endless circuit and being doubled on itself to form two strands lying side by side and in contact both where they pass around the wheels and in the runs between the wheels, said strands crossing in one run of the cable.

2. The combination with two wheels having grooves, of a cable connecting the same, said cable being endless and doubled on itself to form two strands lying side by side in a

single groove of each wheel, the said strands crossing one another in one run of the cable and said strands being in contact with one another throughout their length.

5 3. The combination with two wheels, of a cable connecting the same, said cable constituting an endless circuit and being doubled on itself to form two strands lying side by side and in contact with one another both 10 where they pass around the wheels and in the runs between the wheels, said strands cross-

ing in one run of the cable, one of said wheels having the wall of its groove provided with a notch for the purpose stated.

In testimony whereof, I have hereunto set 15 my hand at Los Angeles, California, this 28th day of September 1908.

MILO A. BAKER.

In presence of—

FREDERICK S. LYON,
FRANK L. A. GRAHAM.
